DESIGN FOR A BATHTUB

Jacques Stanitz, Warren, Ohio, assignor to
Mullins Manufacturing Corporation, Salem,
Ohio, a corporation of New York

Application August 31, 1945, Serial No. 121,767

Term of patent 7 years

(Cl. D4—4)

To all whom it may concern:

Be it known that I, Jacques Stanitz, a citizen of the United States, residing at Warren, in the county of Trumbull and State of Ohio, have invented a new, original, and ornamental Design for Bathtub, of which the following is a specification, reference being had to the accompanying drawing, forming part thereof.

I claim:

The ornamental design for a bathtub, substantially as shown.

JACQUES STANITZ.
